COLLAPSIBLE TUBE ROLLER

Albert H. Jung, Flushing, N. Y., assignor to Victor Industries Corporation, Brooklyn, N. Y., a corporation of New York

Application July 20, 1949, Serial No. 105,831

10 Claims. (Cl. 222—99)

1

This invention relates to rollers for flattening and winding up the emptied end portions of collapsible tubes thereby to effect the overall shortening of the tube, progressively as its contents are dispensed.

The invention contemplates the provision of a two-part tube roller so designed that the parts may be quickly and easily telescoped into each other and secured together against separation other than deliberate and with the clipped end portion of a collapsible tube adequately secured therein, the tube itself serving to lock the roller parts together against relative rotation.

The invention further contemplates the provision of a roller made of two complementary and similar hollow cooperating resilient parts adapted to be assembled with a snap action by merely pressing the parts together in a longitudinal direction, and each having a slot for the passage of the flattened and clipped end portion of a collapsible tube whereby the roller may be operated as a unit to wind or roll up the tube as the latter is emptied, each roller part being closed at its outer end by a winding head or disc which also prevents accidental detachment of the roller parts from the tube by movement in a direction transversely of the tube.

The invention further contemplates the provision of separable fastening means in the form of a bead on one roller part and a groove in the other roller part to receive the bead for firmly but removably holding the roller parts together against longitudinal separation or displacement.

The invention further contemplates the provision of a simple tube winding roller of pleasing appearance adapted to be inexpensively made of suitable slightly resilient synthetic plastic resin or the like material and separable into two similar though complementary parts when removed from the completely emptied tube, the roller parts being easily secured at opposite edges of a full or partly full tube and to each other.

The various objects of the invention will be clear from the description which follows and from the drawings, in which:

Fig. 1 is a vertical sectional view taken through the slots thereof, of the roller parts as they appear separated from each other, the clipped end portion of the tube to which the roller parts are attached being shown by dash-dot lines.

Fig. 2 is a front elevational view partly broken away, of the roller as it appears assembled and attached to the flattened and clipped end portion of a full or fresh tube.

Fig. 3 is a side elevational view of the grooved

2

roller part and of a partly rolled up collapsible tube holding said roller part, the other or beaded roller part having been removed to expose the grooved roller part.

Fig. 4 is a vertical sectional view taken on the line 4—4 of Fig. 1, of the grooved roller part.

Fig. 5 is a similar view taken on the line 5—5 of Fig. 1 of the beaded roller part.

Fig. 6 is a fragmentary horizontal sectional view of the partly assembled roller parts and tube taken on the line 6—6 of Fig. 1 but showing the beaded roller part inserted partway into the grooved roller part and expanding the latter.

As has been indicated, in the practical embodiment of the invention illustrated, the tube roller is made of two similar though complementary slotted and flanged parts as 10 and 11 each preferably molded in one piece of a suitable synthetic thermosetting or thermoplastic resin having some resilience. Each of the parts is flanged or headed at one end as 13 to provide a suitable finger-operable winding member adapted to assume a pleasing form and to be provided with surface ornamentation if desired on its outer surface 14.

20 A tubular member 15 having a longitudinal opening 12 therethrough projects axially from the head 13 of each roller part and is provided with a longitudinal slot 16 extending preferably throughout the length thereof for the reception 30 of a flattened part 18 above the usual flattened and clipped part 17 of the tube end as shown in Figs. 1-3 and 6, whereby the clipped end 17 may be arranged in the longitudinal opening 12 of the tubular members 15.

35 While the division of the roller into two parts permits it to be quickly and easily attached to the tube 18 in such a manner that after assembly of the parts the roller remains securely in place and cannot become detached or lost, the parts

40 are so shaped that they may adequately and securely assembled to each other and to the tube by a single movement toward each other and transversely of the collapsible tube, and yet may be detached from each other and from the tube

45 by a simple movement in the opposite direction or away from each other when the tube is empty or before if desired. For these purposes, the inner end portions of the members 15 of the respective parts 10 and 11 differ somewhat, one being in the form of a female or grooved fastener element and the other in the form of a male or stud fastener element. As best seen in Fig. 1, a relatively wide annular circumferentially arranged groove 20 is recessed into the inner wall

50 of the roller part 10 in longitudinal spaced re-

lation to the annular end edge 19 of said part, and the inner diameter of the open end portion of the inner wall 21 of said roller part is enlarged to a size slightly less than that of the bottom wall of said groove 20 to provide an annular narrow shoulder 22 therebetween.

The outer diameter of the tubular open end portion of the roller part 11 is reduced to correspond to the enlargement of the inner wall 21 of the roller part 10 above described and to fit thereinto, the walls 21 and 25 therefore being of the same diameters and lengths. The male fastener element comprises a bead 23 formed at the extremity of said open end portion 25, the outer diameter of the bead being substantially equal to the diameter of the bottom wall of the groove 20, but the width of the bead being less than the width of said groove. The leading edge of the bead 23 is rounded as best seen in Fig. 1 to produce the desired cam action to permit the parts 10 and 11 to be easily telescoped into each other as indicated in Fig. 6. The trailing edge 26 of the bead forms a shoulder thereon engaging the shoulder 22 when the parts are telescoped together.

Since the respective lengths and diameters of the walls 25 and 21 are substantially the same, the shoulder 24 at the end of the surface 25 will abut against the complementary end edge 19 of the part 10 when the parts are assembled with the bead 23 in the groove 20 as shown in Fig. 2. The outer surface of the part 11 at 25 will also contact the inner surface 21 and the shoulder 26 of the bead 23 will also be substantially in contact with the shoulder 22 of the part 10. Consequently, in said assembled position, the parts cannot easily become separated since the bead shoulder 26 cannot easily pass the cooperating holding shoulder 22. However, since the parts 10 and 11 are sufficiently resilient and are slotted as well, and the difference in diameters of the bead 23 and the wall 21 is slight, a firm pull on the members 13 away from each other causes the bead to expand or to stretch the open end portion of the part 10, the slot 15 aiding to permit such expansion, whereby the bead may be pulled out of the part 10 and the parts separated for use on a fresh or full tube.

To attach the separated roller parts to the clipped or lower end 17 of the full tube, the usual clip at said end 17 is inserted sidewise, that is, by a movement in a direction transversely of the tube into the opening 12 of the part 10 and the corresponding central opening in the part 11, while the flattened part of the collapsible tube above the clip enters the slots 15 as shown in Fig. 1. The bead 23 is then forced into the open end of the part 10 as shown in Fig. 6, thereby expanding said end and the slot of said roller part sufficiently to permit the bead to be forced along the wall 21 until it snaps into the groove 20 and the edge 19 engages the shoulder 24 thereby preventing further telescoping movement of the parts. On release of the pressure put thereon by the bead, the tubular portion of the part 10 contracts to its initial or normal diameter thereby to hold the roller parts securely together. The tube 18, extending as it does, through the slots of both parts 10 and 11, serves as a lock to prevent relative rotation of said parts. Passage of the clipped end 17 of said tube upwardly through the slots 15 is prevented because the slots are made of lesser width than the thickness of the clipped end. It will therefore be seen that when the roller parts are as-

sembled with the tube as above described, they cannot become accidentally detached from each other or from the tube, but can readily be removed by a pull to withdraw the bead from its groove as hereinbefore explained.

It will be understood that the roller may be made in various sizes to fit various standard tubes and in various shapes, that it is adapted to carry surface ornamentation, that it may readily be operated by the fingers of the user after enough of the contents of the tube have been dispensed to flatten the end portion thereof remote from the cap, that the flanges or heads 13 provide effective finger grips for such operation upon the capped tube as to wind up the flattened part of the tube compactly as shown in Fig. 3, that the roller may be quickly and easily attached and assembled by unskilled persons and as easily disassembled for reattachment to another tube, and that I have provided a device adapted to perform its intended purposes effectively.

It will also be seen that each of the roller parts may be readily and inexpensively molded of synthetic plastic in one operation and in one piece, the dimensions of the groove and of the cooperating bead and the resiliency of the slotted parts being such as to permit the parts to be removed from the molds by slight force exerted thereon to expand the grooved part or slightly to compress the beaded part.

While I have shown and described a certain specific embodiment of the invention, it will be understood that various obvious changes may be made therein without departing from the spirit of the invention defined in the appended claims.

I claim:

1. A two-part tube roller comprising a pair of telescoping molded members each having a head and a longitudinally slotted tube projecting from the head, and cooperating separable fastening means on the members comprising an enlarged annular bead providing an integral ridge on the outer wall of one of the members removably entering a corresponding annular groove providing a shouldered recess in the inner wall of the other member, the diameter of that part of the inner wall outwardly of the recess being less than the greatest diameter of the enlarged bead whereby the bead expands the inner wall during the passage of the bead longitudinally into the recess.

2. A collapsible tube roller comprising a first slotted tube closed at one end and open at the other and having a circumferential groove in the inner wall thereof and a second slotted tube closed at one end and open at the other and having an outstanding circumferential bead on the outer wall thereof adjacent the open end and of the same outer diameter as that of the groove, said second tube telescoping into and expanding the first tube until the bead enters the groove, the bead and the groove each terminating in an annular shoulder, the shoulder of the bead being of substantially the same inner and outer respective diameters as the inner and outer diameters of the shoulder of the groove.

3. The tube roller of claim 2, the bead being arranged at the end of the second tube, said second tube having the open end portion thereof beyond the bead reduced in diameter to the diameter of the open end portion of the first tube beyond the groove.

4. The tube roller of claim 2, each of the tubes having an outstanding head at the closed end thereof, the outer wall of the second tube beyond the bead being of substantially the same

diameter as the inner wall of the first tube beyond and adjacent to the groove.

5. The tube roller of claim 2, an outstanding head at the closed end of each of the tubes, there being a longitudinal slot in each of the tubes extending from the open end to the head thereof.

6. The tube roller of claim 2, the bead being rounded at its leading edge, the shoulder of the bead engaging the shoulder of the groove when the bead is in the groove, each of the tubes having a longitudinal slot therein extending from the open end thereof up to the closed end thereof.

7. A collapsible tube roller comprising a resilient one piece roller tube closed at one end and having a longitudinal slot through the remainder thereof and open at the other end thereof, there being an annular groove arranged circumferentially around and recessed into the inner wall of the tube, and a second roller tube closed at one end and having a longitudinal slot through the remainder thereof and open at the other end thereof and having an annular projection thereon fitting into and entering and cooperating with the groove to maintain the tubes against separation when the tubes are forcibly telescoped together, the greatest normal diameter of the bead being greater than the normal inner diameter of the open end part of the first roller tube, thereby requiring expansion of the first tube and the widening of the slot thereof to permit the bead to pass into the first tube up to the groove.

8. The collapsible tube roller of claim 7, the slots of the roller tubes being locked in align-

ment with each other when in use by a collapsible tube having a flattened portion thereof arranged in the slots and having an end portion arranged in the interior of the tubes.

5. The collapsible tube roller of claim 7, each of the tubes having an outstanding winding head at the closed end thereof.

10. In a tube roller, a longitudinally slotted tubular member having a circumferential ridge on its outer surface terminating in an annular shoulder, and a longitudinally slotted sleeve having a circumferential recess in its inner surface adapted to receive the ridge when the member is forced into the sleeve to a position wherein the ridge registers with the recess, the greatest diameter of the ridge being greater than the inner diameter of the sleeve to expand the sleeve as the member and the sleeve are telescoped together, the shoulder of the member engaging the shoulder of the sleeve to detachably lock the member and the sleeve together.
